United States Patent Office.

JOHN ROGERS, OF NEW YORK, N. Y.

Design No. 3,364, dated February 9, 1869.

DESIGN FOR A GROUP OF STATUARY.

The Schedule referred to in these Letters Patent and making part of the same.

To all whom it may concern:

Be it known that I, JOHN ROGERS, of the city, county, and State of New York, have invented or produced a new and original Design for a Group of Statuary; and I do hereby declare that the following is a full and exact description of the same.

It consists of three figures, and is called "Challenging the Union Vote." It represents an old Unionist, who comes with his granddaughter, and is about to deposit his vote in the ballot-box on the desk, but is stopped by the inspector, who is seated at the desk, and pushes his hand one side, while he runs his eye

over the registry to find his name; all of which is fully shown in the accompanying drawings.

Having thus described my invention,

What I claim, and desire to secure by Letters Patent, is—

The design for a group of statuary, as herein shown and described.

JOHN ROGERS.
